REFRIGERATING APPARATUS

Floran L. Meacham, Dayton, Ohio, assignor to
General Motors Corporation, Dayton, Ohio, a
corporation of Delaware

Application February 23, 1935, Serial No. 7,675

2 Claims. (Cl. 211—153)

This invention relates to refrigerator cabinets and particularly to a shelf for use therein.

An object of the present invention is to provide a novel method of making an improved type of food supporting shelf for refrigerator cabinets.

Another object of the invention is to provide an improved type of shelf having a perfectly plane or flat surface for supporting articles and particularly small containers without causing 10 tilting or upsetting thereof.

A further object of the invention is to provide an improved shelf for a refrigerator cabinet which will not interfere with circulation of air in the refrigerator and which can be manufactured at low cost.

A still further object of the invention is to provide a shelf for a refrigerator cabinet which will have a minimum of cross pieces as compared to conventional shelves and which will be devoid of sharp edges to thereby render the shelf easily 20 cleanable.

Further objects and advantages of the present invention will be apparent from the following description, reference being had to the accompanying drawing, wherein a preferred form of the 25 present invention is clearly shown.

In the drawing:

Fig. 1 discloses a refrigerator cabinet of the household type with the food compartment door 30 thereof in open position and showing shelves constructed according to the present invention disposed in the compartment;

Fig. 2 is an enlarged fragmentary horizontal view through the cabinet shown in Fig. 1 showing my improved shelf supported in the food storage compartment of the cabinet;

Fig. 3 is a fragmentary view of a round bar or wire employed in the construction of my improved shelf and showing a portion thereof as 40 being flattened;

Fig. 4 is an end view of the bar or rod shown in Fig. 3;

Fig. 5 is a side view of a bar or rod after having been flattened as shown in Figs. 3 and 4 and after 45 having openings punched therethrough;

Fig. 6 is an elevational side view of a device for holding a plurality of the rods shown in Fig. 5 in alignment during the manufacture of my improved shelf; and

Fig. 7 is a sectional view of the device shown in Fig. 6 and is taken on the lines 7—7 thereof.

In the construction of refrigerators and particularly those of the mechanically refrigerated household type difficulty has been experienced in 55 providing satisfactory means within the cabinet

for supporting objects to be cooled. Conventional shelves heretofore employed in refrigerator cabinets have been constructed of lattice work or gratings or the like of woven wire and these conventional shelves have not been entirely satisfactory. One of the difficulties in the use of shelves heretofore employed consists in supporting small containers without upsetting or causing them to tilt so as to cause the contents to spill. Another difficulty encountered in the use of food 10 supporting shelves in refrigerators is that the conventional shelves ordinarily consist of entirely too many cross pieces which have sharp corners or edges thereby rendering the shelves hard to clean. The plurality of cross pieces and sharp 15 edges ordinarily found in conventional shelves interfere with the sliding of objects or containers along the supporting surface of the shelves during the act of moving containers into and from the food compartment of refrigerator cabinets. 20 These and other difficulties are eliminated by the use of the improved type of shelf of the present invention.

Referring to the drawing, for purposes of illustration, I have shown in Fig. 1 thereof a refrigerator cabinet 10 of the household type. The cabinet 10 includes a plurality of vertically disposed and suitably insulated walls 11 and horizontally disposed insulated walls 12 forming and surrounding a food storage compartment 13. The compartment 13 has an opening therein which permits access to the interior thereof and which opening is ordinarily closed by a door 14. A cooling element or evaporator 15 is mounted within compartment 13 and is adapted to be connected with any suitable or conventional refrigerant liquefying and circulating unit (not shown). The inner surface of the insulated walls 11 and 12 forming food storage compartment 13 are lined with a metallic lining member 16 upon which 40 horizontally aligned means or protrusions 17 are provided for supporting a plurality of vertically spaced apart and horizontally extending food supporting shelves 18. The shelves 18 divide the compartment 13 into a plurality of superimposed 45 food storage chambers and the cooling effect produced by the evaporator 15 causes circulation of air throughout compartment 13 and between the food chambers therein for chilling food products adapted to be stored in the cabinet 10.

Having described the construction of the cabinet 10 and arrangement of the shelves employed therein I will now proceed to describe the construction and method of making the shelves 18. A plurality of pieces of round wire or round rods 55

21 of a predetermined and similar length are cut from a roll thereof or from a long piece of rod or wire. These similar lengths of round wire 21 are then flattened as at 22 (see Figs. 3 and 4) by 5 any suitable means to provide the flat bar 23 shown in Fig. 5. The lengths of round rods or wires 21 may, for example, be progressively flattened along the length thereof by forcing them through rollers or the like or they may be flattened simultaneously throughout their length in 10 a press, if desired. On the other hand a long straight continuous rod or wire may be drawn or forced through suitable pressing rollers to progressively flatten the rod or wire along the continuous length thereof prior to cutting the predetermined lengths or bars therefrom. It is to be 15 understood that suitable provisions for maintaining the curved smooth edges 24 of the bars 23 in a flat plane and parallel with one another must be provided during the act of flattening the wires or rods 21. After obtaining a plurality of the flattened bars 23 as shown in Fig. 5 of the drawing in the manner described an opening or hole 26 is punched or cut through the bar 23 at or 20 near each end thereof. Each of the holes 26 in rod 23 are of an elongated formation and the elongation extends in a direction parallel with the longitudinal extension of the rod 23. It is to be understood that the holes or openings 26 in the 25 flat bar 23 are equally spaced apart and are equally spaced from the ends of the bar. A plurality of the flat bars 23 shown in Fig. 5 of the drawing are then placed in a rack or aligning device 28. The device 28 includes a base portion 29 and raised end portions 31. Device 28 is also provided with a plurality of parallelly extending grooves or slots 32 cut in the upper face of the base portion 29 thereof. Each of the grooves 32 is adapted to receive one of the flattened bars 40 or rods 23 and it will be noted that the ends of rods or bars 23 abut the inner wall surface of the end portions 31 of device 28 to align the elongated openings 26 in the plurality of bars or rods 23. After having positioned the rods 23 in 45 the grooves 32 of device 28, so that the openings 23 and the rods or bars are in horizontal alignment with one another, a rod 34 is adapted to be forced through each of the aligned set of holes or openings 26. The rods 34 adapted to be forced 50 through the elongated holes 26 in bars 23 are substantially oval or elongated in cross-section and are formed by flattening a round shaft in the same manner that the flattening of bars 23 is carried out. The oval or elongated in cross-section rods 34 are positioned transversely to the bars 23 and are adapted to be forced, by any suitable forcing means, into each of the elongated holes 26 in the aligned sets thereof in bars 23. Rods 34 tightly engage walls of the openings 26 in bars 23, and this tight fit prevents movement of the bars 23 along the length of rods 34 and also eliminates the necessity of soldering or welding the bars and rods together. It will be seen that the elongated shape of the 65 holes 26 in bars 23 and the oval or elongated cross-sectional contour of rods 34 prevents rotation of the rods 34 in the holes 26. Thus the rods 34 and holes 26 in bars 23 maintain the plurality of bars 23 in horizontal alignment and the 70 bars 23 provide a flat food supporting surface. The rigid structure prevents one end of the shelf 18 from being twisted out of alignment with the other end thereof. After the rods 34 are assembled in the bars 23 to provide a unitary shelf 75 structure the ends of rods 34 may be bent at

right angles to the main portion thereof as indicated at 35. In other words the ends of rods 34 may be bent to extend in the same direction as the extensions of the longitudinal bars 23 so as to provide a wide supporting leg on the shelf for resting on or for attachment to the shelf supports 17 formed on the lining member 16 of cabinet 10.

A shelf 18 constructed as disclosed eliminates the necessity of soldering or welding the joints between the longitudinal bars 23 and the cross rods 34 by virtue of the cooperation of the oval rods 34 with the elongated openings 26 in bars 23 to thereby provide a rigid structure. A shelf constructed according to my invention provides a flat food supporting surface and is adapted to be mounted in a refrigerator cabinet so that the longitudinal bars 23 thereof extend in a direction parallel with the side walls of the cabinet. The extension of the bars 23 of shelf 18 permits articles to be freely slid along the surface of the shelf without striking cross rods since only two cross rods are employed in the construction of the improved shelf, and since these cross rods 34 are positioned below the plane of 25 the round top supporting surface 24 of bars 23.

It will be seen from the foregoing that I have provided an improved shelf construction for use in refrigerator cabinets and that the novel method of making the shelf as disclosed reduces manufacturing costs to a minimum while at the same time provides a strong rigid shelf which will not twist out of a horizontal plane or become deformed. My improved shelf construction greatly reduces the number of cross bars ordinarily employed in conventional shelf structures and thereby facilitates cleaning of the shelf and permits a free air circulation within a refrigerator cabinet. My improved shelf structure also eliminates sharp edges or corners and thereby prevents cutting of the hands during cleaning of the shelf or during the act of placing food products in the food storage compartment or removing same therefrom. In addition my improved shelf provides a flat food supporting surface for supporting small articles or dishes thereon without causing tilting thereof.

While the form of embodiment of the invention as herein disclosed, constitutes a preferred form, it is to be understood that other forms might be adopted, all coming within the scope of the claims which follow.

What is claimed is as follows:

1. A shelf for refrigerators comprising, a plurality of spaced apart members extending longitudinally in the same direction, each of said members having spaced apart openings extending horizontally therethrough in a direction transverse to the length thereof, a pair of spaced apart rods extending transversely to said members through the openings therein and constituting the sole means of supporting said plurality of members in a common horizontal plane, the cross-section of said rods, at least at their point of intersection with said members, being of a special contour relative to the contour of the walls of the openings in said members for rigidly securing the plurality of members in said common horizontal plane to provide a flat surface adapted for the support and ready sliding of objects thereon, and the ends of said rods being extended outwardly from said members to form supporting legs for said shelf.

2. A shelf for refrigerators comprising, a plurality of flat members spaced apart and arranged

so that their flat faces are vertically disposed, said members extending longitudinally in the same direction, each of said flat members having spaced apart openings extending horizontally therethrough in a direction transverse to the length thereof, a pair of spaced apart rods extending transversely to said flat members through the openings therein and constituting the sole means of supporting said plurality of flat members in a common horizontal plane, the cross-section of said rods, at least at their point of in-

tersection with said flat members, being of a special contour relative to the contour of the walls of the openings in said flat members for rigidly securing the plurality of flat members in said common horizontal plane to provide a flat surface adapted for the support and ready sliding of objects thereon, and the ends of said rods being extended outwardly of said members to form supporting legs for said shelf.
